Primary Examiner — Austin Murphy**CLAIM**

The ornamental design for a compressor pad, as shown and described.

DESCRIPTION

FIG. 1 is a perspective view of a compressor pad attached to a glue stick.

FIG. 2 is a top view of the compressor pad with the tongue element shown detached for convenience of illustration.

FIG. 3 is the bottom view of FIG. 2;

FIG. 4 is a front view of FIG. 2;

FIG. 5 is the rear view of FIG. 2; and,

FIG. 6 is a side view of FIG. 2.

The broken lines shown in FIG. 1 represent portions of the glue stick that form no part of the claimed design. The non-uniform stippling shown on the compressor pad in FIGS. 1, 2, 4, 5, and 6 represents a cloth/felt surface texture. The uniform stippling shown in FIG. 3 represents an adhesive surface on the bottom portion of the compressor pad.
